UNITED STATES PATENT OFFICE.

JOHN LANE, OF BROOKLYN, NEW YORK, ASSIGNOR TO L. PRANG & CO., OF BOSTON, MASSACHUSETTS.

ORNAMENTAL CARD.

SPECIFICATION forming part of Letters Patent No. 279,490, dated June 12, 1883.
Application filed February 23, 1883. (No model.)

To all whom it may concern:

Be it known that I, JOHN LANE, of the city of Brooklyn, in the county of Kings and State of New York, have invented a new and useful Improvement in the Manufacture of Decorated Cards for Ornamental and other Purposes, of which the following is a specification.

My invention has reference to certain classes of printed and otherwise ornamented work, known as "birthday," "New-Year," and "Christmas" cards, &c.; and its special object is the construction of an ornamental card designed for the preservation and convenient display of mementos and souvenirs, which have peculiar interest and value for the possessor, in an appropriate and convenient manner. For this purpose I construct a card in a novel way, which the accompanying drawings will make intelligible.

Figure 1 shows the front elevation of such a card. Fig. 2 is a back elevation of the same. Fig. 3 is a cross-section on line 1 1. Fig. 4 is a view, looking from above downward on the edge of the card. Fig. 5 is the elevation of the back of a similar card modified in construction. Fig. 6 is a section on line 3 3 in Fig. 5, showing its door open. Fig. 7 is a section of the same on line 2 2. Figs. 8 and 9 are cross-sections illustrating modifications in construction. Fig. 10 is the front elevation of an attachment desirable in some cases. Fig. 11 is a cross-section of the same on line 4 4. Fig. 12 is a partial elevation, showing a detail of construction on a large scale.

The front of a card constructed in accordance with my invention is shown in Fig. 1. It may be ornamented with any appropriate design drawn or painted by hand, or produced by chromographic or other printing, or by embossing, or by a combination of any two or all of these methods. In practice, however, I use, and much prefer to use, the chromolithographic process for this purpose, it being by far the most effective for decorative ornamentation, and especially in this case for the production of the large number of designs required to form appropriate and harmonious combinations with the various articles to be exhibited. Such appropriateness constitutes an important factor in the value of the finished

product which my invention contemplates. A card of this kind consists of two or more pieces pasted together, and, as in the figures, the central part, at *a*, of the front thickness of cardboard is cut out and removed, leaving an aperture of any suitable shape. In this opening, or immediately behind it, as in the drawings, a thin piece of transparent gelatine tissue (marked *a* in all the figures,) is securely attached. I prefer clear sheet-gelatine for this purpose, because of its lightness and elasticity, which greatly facilitate the safe packing, transportation, and handling of the cards when finished; but I also use other transparent or sufficiently transparent materials, such as mica, very thin sheets of horn, and in some cases, in which a certain degree of obscurity is wished, fine paper made transparent by means of varnishes, &c. Immediately behind the gelatine window a receptacle or pocket, *b*, is formed, which may be, in most cases, quite shallow. This is best done by introducing a piece, *c*, between the back and front layers of card-board, *e* and *d*, respectively, with an opening in it, the form of which is indicated in Figs. 2 and 5 by the dotted lines marked *f*; but this piece may sometimes be omitted and a like pocket left by simply applying the paste so as not to cement the back and front pieces of card-board where said pocket is required. This space must be accessible from the outside of the card, and in Figs. 1, 2, 3, and 4 the flat chamber *b* is open, with this end in view at the upper edge of the card, as will be seen distinctly in Fig. 3, showing the card in section, and in Fig. 4, which is a plan of the same, looking down upon the edge.

The souvenir or memento, be it a lock of hair, a dried flower, an autograph, a manuscript poem, an original sketch, a photograph, or a fragment of rock from some interesting locality, is slipped in between the transparent gelatine and the back wall, *e*, of the chamber or pocket. In this position it is visible from the outside, and forms, with the card, a compact and harmonious whole, which can be shown to advantage and handled without risking the loss or injury of the object so preserved. When access is had to the space behind the gelatine from the edge of the card, as in Figs. 1, 2, 3, and 4, the opening left for this purpose

may be closed after the object is introduced, so as to exclude dust and prevent other mischance, by simply gumming the edges together; or a flap with a tongue to enter a slit may be used for that purpose, in the manner employed to close temporarily certain kinds of envelopes and manila-paper boxes, the construction of which is well known and understood. To facilitate getting the object (especially if it be of a fragile nature) into proper position, an attachment for souvenir-cards of this description may be provided, which is shown in elevation and cross-section in Figs. 10 and 11. This consists of a strip of strong paper, *g*, re-enforced 5 at its upper part with one of card-board, *h*. The object to be preserved is first attached to the paper at the part marked *g* by cement or otherwise, and the whole attachment, which fits the pocket in size, is then slipped into place, 10 the strip of card-board *h* filling the entrance to the receptacle completely.

The essential features of my invention above set forth may be preserved, notwithstanding certain modifications in detail, some of which 15 I will now describe.

Instead of providing access to the receptacle behind the window of gelatine by means of a slit in the edge of the card, as in Figs. 1, 2, 3, and 4, a flap or door, *i*, in Figs. 5 and 6, may 20 be hinged at the back of the card by cutting the card-board forming the back *e* partly through one edge of the door and completely through the other three edges, or by means of the paper strip *k*, pasted over the joint, when 25 all four edges have been cut through, as in Figs. 5 and 6. Between this door and the transparent medium in front the object to be displayed is placed, and when closed the door may be fastened by the little piece of gummed 30 paper *l*, or in any other convenient way; or, as in Fig. 8, the door *i*, which gives access to the chamber, may be in front, carrying with it the transparent film of gelatine; and, as in the previous case, this door may be hinged by 35 a strip of paper or similar substance at one edge, and fastened by gummed paper or otherwise at the other. Both these modifications are useful when the object to be preserved is delicate and requires careful handling, or when 40 a chamber having some depth is desired.

I also construct souvenir-cards in which both sides of the pocket or chamber are provided with transparent walls in a manner made intelligible by Fig. 9, which may be regarded as 45 a cross-section of Fig. 1, when so modified, on line 11, the letters of reference used before indicating corresponding parts. Both sides of the card are then usually ornamented, as of course they may be in all souvenir-cards of 50 this kind. In this section, Fig. 9, it will be seen that two pieces of gelatine, *a* and *a'*, are used to close the openings in both back and front, *e* and *d*, while access to the pocket is from the upper edge, as in Figs. 1, 2, 3, and 4. 55 Cards of this description are employed when both sides of the object to be preserved are of

interest, or when it is wished to exhibit it by transmitted light.

In some cases, also, an initial, monogram, or other ornament may be printed or drawn 70 upon the transparent substance used in the fabrication of souvenir-cards, so as partially to obscure the relic preserved behind it; and on the front or back of all cards of the kind I have invented provision may be made and 75 suitable space set apart for the insertion of names or dates having reference to the mementos to be preserved therein.

It will be readily understood that there are other ways besides those described of construc- 80 ting the flat pocket or chamber and covering it with the transparent medium on one or both of its sides, and that I therefore do not limit myself to such methods. Nor is it necessary that said receptacle should always be situated 85 in the middle of the card, as shown in the drawings, for it may be placed at any part of the same, so as best to harmonize with the general design; and although card-board is spoken of in the foregoing, other substances 90 may be employed in conjunction therewith— as, for instance, silk, velvet, or similar material, and thin veneers of wood, &c., with or without designs printed, painted, or impressed thereon. Fringes, tassels, or cords can also be 95 applied for purposes of ornament, as they now are on similar manufactured articles; and although the transparent substances used in carrying out my invention have been hitherto spoken of, and shown in the drawings, as tak- 100 ing the form of flat, thin sheets, yet it is evident that such transparent bodies may be bent or molded so as to assume cylindrical or spherical curves, and still perform their function in the production of cards of the kind herein de- 105 scribed, sometimes with positive advantage, due to their increased strength, &c.

In addition to what has been above set forth, it should also be stated that, although the edges of the sheet of gelatine tissue or other 110 transparent substance made use of in the fabrication of souvenir-cards may be pasted or glued rigidly and firmly to the surface of the card-board employed, still I prefer not to make the attachment in this way, but rather to give 115 the gelatine opportunity for a certain slight amount of free movement. This may be accomplished in various ways, the object being to let the transparent medium and the card-board expand and contract independently of 120 each other. Atmospheric changes affect differ- 125 ently or in a different degree the size of the gelatine, (or that of any one of the substitutes for it hereinbefore named,) and the material from which the body of the card is made, and when the two are connected rigidly the difference in contractibility or expansibility is apt to give rise to irregular buckling of the manufactured article, which, when said difference is considerable, takes from the beauty and 130 finish of its appearance and lessens its value.

In Fig. 12 one very simple but effective way

is shown, on a large scale, by which the transparent material *a* is attached to the card-board *d* so as to allow it sufficient independent movement while it is still held properly in place. 5 One corner only of *a* is shown, over which the strip of thin paper *m* is laid flat, and the ends of this strip are then pasted down, but only as far as the dotted lines at *n*. In this way (the other corners being held in like manner) the 10 transparent medium is kept flat and in its proper place, while it is free to alter in size or not relatively to the card-board against which it lies. It is plain that this detail of construction admits of modification in many ways 15 without affecting the principle involved or the general result.

Having thus described my invention and the way in which the same may be carried out, what I claim, and desire to secure by Letters 20 Patent, is—

1. A chromographic or other ornamental card provided with a pocket or receptacle accessible from without, said pocket being covered on one or both of its sides with a flexible

transparent medium forming part of the same, 25 substantially as and for the purpose described.

2. A chromographic or other ornamental card provided with a pocket or receptacle accessible from without, said pocket being covered by a flexible transparent medium forming 30 part of the same, which is securely but not rigidly attached, whereby the flexible transparent medium and the card-body can expand or contract independently of each other, substantially as and for the purpose set forth. 35

3. A chromographic or other ornamental card provided with an accessible pocket or cavity covered with a piece of sheet-gelatine or other flexible transparent medium forming 40 part of the same, and with means for permanently or temporarily closing the opening giving access to said pocket, substantially as and for the purpose set forth.

JOHN LANE.
